UNITED STATES PATENT OFFICE

2016.01.20. 10:00 AM - 10:30 AM. **MIXING** **2,460**

George A. Engert, Westfield,
Cheney Bigelow Wire Works,
a corporation of Massachusetts,
Application July 26, 1919.

This invention relates to mixing apparatus and is directed more particularly to mixing box adapted for use in connection with paper making operations.

The principal objects of the invention are the provision of a mixing box of novel form and construction for mixing stock for paper making operations and is characterized by its simplicity and adjustability thereby to enhance its efficiency for mixing paper making stock and water to obtain the desired uniform disposal of stock. While reference is herein made to mixing stock for paper making operations it will be understood that the apparatus is adapted for broad application in connection with the mixing of liquids with fibrous and other materials.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a plan view of a mixing box embodying the novel features of the invention;

Fig. 2 is a sectional elevational view on the line 2—2 of Fig. 1; and

Fig. 3 is a sectional elevational view on the line 3-3 of Fig. 1.

Referring now to the drawings more in detail, the invention will be fully described.

A receptacle or the mixing box proper is indicated by 2 and has a circular wall 4 which extends upwardly from a lower wall 8. The wall 4 extends from a cylindrical portion to the left as in Fig. 1 to conform with an outlet 6 which is provided in said lower wall 8. The side wall and lower wall may be made from metal plate material suitably formed and secured together as by welding and there may be a reinforcing band 10 around the upper side of the box as shown.

A circular wall 12 extends downwardly from the lower wall 8 which is concentric to the curved part of the wall 4 and it has a lower wall 14 secured thereto. The walls 12 and 14 provide a sump in the lower wall 8.

A circular wall 16 is concentrically disposed

Established in 1966, the National Institute of Child Health and Human Development (NICHD) is the lead federal agency for research on the health and development of children, from birth through adolescence, and on the health of children's parents, including research on the causes and prevention of birth defects and other developmental disabilities.

PATENT OFFICE

626 *Chlorophytum comosum* (L.) Willd. var. *comosum*

STYLING BOX BY JEFFREY BROWN

Cl. 92-37) **2** *Waren und*
andere Sachen, die nicht

relative to the wall 12 and capped by an upper wall 18 which is secured thereto. Said walls 16 and 18 provide a dome 20 which may be secured to the lower wall 14 as by welding at 22.

A water inlet 24 is provided which leads into the sump at one side thereof and a stock inlet 26 is provided which also leads into the sump at another side thereof. It is desirable that these inlets 24 and 26 be located substantially opposite to one another and adjacent the bottom wall 14 below the plane of the upper portion of the dome 20.

20. A cylinder 28 which may be called a gate is provided and is concentrically disposed relative to the side wall 12 of the sump and arms such as 30 have outer ends secured thereto and extend inwardly to an anchor member 30 which is rigidly secured thereto. The arms 30 may take any form desired and they may be secured to the cylinder 28 in any convenient manner as by welding at 34.

A weir 36 is provided which preferably is in the form of a tube or cylindrical rod formed to extend around the upper end of the cylinder 28. Said weir is secured to the cylinder as by welding at 38.

Transverse supporting members 40 extend between opposite wall portions of the box and have opposite ends secured to said wall portions. A bracket 42 is secured to the member 40 intermediate opposite ends thereof. A screw 44 has its lower end secured to the member 32 as by a pin 46 and a gear 48 is internally screw threaded for threadedly engaging said screw 44 and rests on the member 42.

A shaft 50 is rotatable in bearings 52 which are secured to plates 54 that are fixed to the members 40. Said shaft has a pinion 56 on its inner end which is in engagement with the gear 48 and a hand wheel 58 is secured to the outer end of said shaft 50.

As the shaft 50 is rotated in one direction or the other the gear 48 is rotated in one direction or the other whereby the shaft 44 being in threaded engagement with the gear the cylinder is raised and lowered relative to the sump and the dome 20 to position the weir relative to the stock level in the box.

Stock is delivered through the inlet 26 while water is delivered through inlet 24 in such velocity as may be desired and so that in the lower part of

the sump around the dome 20 there is a considerable turbulence thereby to insure a thorough mixing of the stock and water. The water which is admitted to the sump may be white water from a paper machine.

The mixed stock and water flow upwardly within the sump so that above the dome there is relatively less velocity and turbulence than around the dome and adjacent the lower wall. As the mixed stock and water rise upwardly within the cylinder 28 the velocity tends to become somewhat less than at points therebelow. The mixed stock and water flow over the weir 36 into the delivery chamber which extends around the cylinder 28.

The cylinder will be raised or lowered depending upon the level of stock in the delivery chamber which for illustrative purposes is indicated by L in Fig. 2. It is desirable that the mixed stock and water as it flows or spills over the weir from the cylinder 28 does not create sufficient turbulence to create foam. The construction is such that it is possible for the mixed stock and water to flow uniformly at 6 from the delivery chamber with minimum turbulence and at a desired maximum velocity without the creation of foam.

The cylinder 28 may be adjusted up and down as may be desired in order to obtain the desired results. If it is desired in the broad aspects of the invention that the stock and water enter the sump at such velocity and create such turbulence as will bring about the desired mixing of the stock and water while the same flows upwardly with decreasing velocity and turbulence so that as the stock and water flow over the weir the stock is uniformly mixed and the mixed stock and water are delivered from the delivery chamber with the least turbulence consistent with the velocity desired. The weir is of considerable length thereby making it possible for a considerable flow of stock and water to take place without creating turbulence which results in foam and is objectionable.

It may be desired to provide dump valves in the walls 8 and 14. As shown in Fig. 1 valves such as 60 are pivotally connected at 62 to arms 64 of levers 66 which pivoted at 68 to brackets 70 secured to the wall 8. An outlet member 72 is secured to said wall which has opening 74 therethrough in which valve 60 seats. By moving lever 66 upwardly the valve 60 is moved from off its seat to provide a free passageway through member 72.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A mixing box construction comprising in combination, a horizontal lower wall and a continuous vertical side wall extending upwardly therefrom and forming therewith a chamber, said side wall at one side of the chamber arranged in the form of a portion of a circle of certain radius and at an opposite side thereof in the form of a portion of a circle of relatively shorter

radius providing a main portion and an outlet portion of said chamber, said lower wall provided with a sump opening and an outlet opening and disposed in the main and outlet portions of the chamber respectively, a cylindrical side wall extending downwardly from said lower wall around the sump opening therein and a lower wall secured to the lower end of said cylindrical side wall forming therewith a sump below said lower wall, said cylindrical wall of the sump provided with inlet means to admit water and paper stock, a hollow cylindrical gate having a lower portion within said sump and a continuous upper edge adapted for the flow of water and stock from 10 said inlet means upwardly therethrough and over said upper edge and at all sides thereof into said chamber, and said upper edge of the gate provided with an overflow weir extending entirely therearound.

2. A mixing box construction comprising in combination, a horizontal lower wall and a continuous vertical side wall extending upwardly therefrom and forming therewith a chamber, said side wall at one side of the chamber arranged 25 in the form of a portion of a circle of certain radius and at an opposite side thereof in the form of a portion of a circle of relatively shorter radius providing a main portion and an outlet portion of said chamber, said lower wall provided with a sump opening and an outlet opening and disposed in the main and outlet portions of the chamber respectively, a cylindrical side wall extending downwardly from said lower wall around the sump opening therein and a lower wall secured to the lower end of said cylindrical side wall forming therewith a sump below said lower wall, said cylindrical wall of the sump provided with inlet means to admit water and paper stock, a hollow cylindrical gate having a lower portion 35 within said sump and a continuous upper edge adapted for the flow of water and stock from said inlet means upwardly therethrough and over said upper edge and at all sides thereof into said chamber, and said upper edge of the gate provided with an overflow weir extending entirely therearound, and operating means between the upper sides of said gate and side wall for moving said gate up and down relative to said sump.

3. A mixing box construction comprising in combination, a horizontal lower wall and a continuous vertical side wall extending upwardly therefrom and forming therewith a chamber, said side wall at one side of the chamber arranged 40 in the form of a portion of a circle of certain radius and at an opposite side thereof in the form of a portion of a circle of relatively shorter radius providing a main portion and an outlet portion of said chamber, said lower wall provided with a sump opening and an outlet opening and disposed in the main and outlet portions of the chamber respectively, a cylindrical side wall extending downwardly from said lower wall around the sump opening therein and a lower wall secured to the lower end of said cylindrical side wall forming therewith a sump below said lower wall, said cylindrical wall of the sump provided with inlet means to admit water and paper stock, a hollow cylindrical gate having a lower portion 45 within said sump and a continuous upper edge adapted for the flow of water and stock from said inlet means upwardly therethrough and over said upper edge and at all sides thereof into said chamber, and said upper edge of the gate provided with an overflow weir extending entirely therearound, and operating means between the upper sides of said gate and side wall for moving said gate up and down relative to said sump.

5. A mixing box construction comprising in combination, a horizontal lower wall and a continuous vertical side wall extending upwardly therefrom and forming therewith a chamber, said side wall at one side of the chamber arranged 50 in the form of a portion of a circle of certain radius and at an opposite side thereof in the form of a portion of a circle of relatively shorter radius providing a main portion and an outlet portion of said chamber, said lower wall provided with a sump opening and an outlet opening and disposed in the main and outlet portions of the chamber respectively, a cylindrical side wall extending downwardly from said lower wall around the sump opening therein and a lower wall secured to the lower end of said cylindrical side wall forming therewith a sump below said lower wall, said cylindrical wall of the sump provided with inlet means to admit water and paper stock, a hollow cylindrical gate having a lower portion 55 within said sump and a continuous upper edge adapted for the flow of water and stock from said inlet means upwardly therethrough and over said upper edge and at all sides thereof into said chamber, and said upper edge of the gate provided with an overflow weir extending entirely therearound, and operating means between the upper sides of said gate and side wall for moving said gate up and down relative to said sump.

6. A mixing box construction comprising in combination, a horizontal lower wall and a continuous vertical side wall extending upwardly therefrom and forming therewith a chamber, said side wall at one side of the chamber arranged 60 in the form of a portion of a circle of certain radius and at an opposite side thereof in the form of a portion of a circle of relatively shorter radius providing a main portion and an outlet portion of said chamber, said lower wall provided with a sump opening and an outlet opening and disposed in the main and outlet portions of the chamber respectively, a cylindrical side wall extending downwardly from said lower wall around the sump opening therein and a lower wall secured to the lower end of said cylindrical side wall forming therewith a sump below said lower wall, said cylindrical wall of the sump provided with inlet means to admit water and paper stock, a hollow cylindrical gate having a lower portion 65 within said sump and a continuous upper edge adapted for the flow of water and stock from said inlet means upwardly therethrough and over said upper edge and at all sides thereof into said chamber, and said upper edge of the gate provided with an overflow weir extending entirely therearound, and operating means between the upper sides of said gate and side wall for moving said gate up and down relative to said sump.

7. A mixing box construction comprising in combination, a horizontal lower wall and a continuous vertical side wall extending upwardly therefrom and forming therewith a chamber, said side wall at one side of the chamber arranged 70 in the form of a portion of a circle of certain radius and at an opposite side thereof in the form of a portion of a circle of relatively shorter radius providing a main portion and an outlet portion of said chamber, said lower wall provided with a sump opening and an outlet opening and disposed in the main and outlet portions of the chamber respectively, a cylindrical side wall extending downwardly from said lower wall around the sump opening therein and a lower wall secured to the lower end of said cylindrical side wall forming therewith a sump below said lower wall, said cylindrical wall of the sump provided with inlet means to admit water and paper stock, a hollow cylindrical gate having a lower portion 75 within said sump and a continuous upper edge adapted for the flow of water and stock from said inlet means upwardly therethrough and over said upper edge and at all sides thereof into said chamber, and said upper edge of the gate provided with an overflow weir ex-

tending entirely therearound, and operating means between upper sides of said gate and side wall for moving said gate up and down relative to said sump, and a dome extending upwardly from the lower wall of the sump having a side wall spaced inwardly from the side wall of said sump and an upper wall disposed above the horizontal plane of said inlet means.
